UNITED STATES PATENT OFFICE

123,297

DESIGN FOR A PENCIL OR SIMILAR ARTICLE

Sylvester G. Lipic, St. Louis, Mo.

Application May 15, 1940, Serial No. 92,379

Term of patent 14 years

To all whom it may concern:

Be it known that I, Sylvester G. Lipic, a citizen of the United States, residing in the city of St. Louis and State of Missouri, have invented a new, original, and ornamental Design for a Pencil or Similar Article, of which the following is a specification, reference being had to the accompanying drawing, forming part thereof.

In the drawing,

Fig. 1 is an elevational view of a pencil embodying my new design as it appears in a vertical position;

Fig. 2 is a longitudinal sectional view of the capsule only.

Figs. 3 and 4 are views similar to Fig. 1, showing my design as it appears in positions deviating slightly from the horizontal.

The distinguishing feature of my invention resides in the portion shown in full lines, comprising a sealed elongated transparent capsule substantially filled with a liquid such as oil, and an unsupported solid of a specific gravity heavier than the liquid immersed in the liquid.

I claim:

The ornamental design for a pencil or similar article, as shown and described.

SYLVESTER G. LIPIC.
